(57) **CLAIM**

The ornamental design for a frame for floral arrangements, as shown and described.

DESCRIPTION

FIG. 1 is a perspective view of a frame for floral arrangements showing the new design;

FIG. 2 is another perspective view thereof, but from the opposite side of that shown in FIG. 1;

FIG. 3 is a top or bottom perspective view thereof;

FIG. 4 is a side perspective view thereof; and,

FIG. 5 is yet another perspective view thereof, showing only a portion of the design shown in FIG. 1.
